(57) **CLAIM**

The ornamental design for a shoe sole, as shown and described.

DESCRIPTION

FIG. 1 is a perspective view of a shoe sole according to the present invention.

FIG. 2 is a front view of the shoe sole of FIG. 1.

FIG. 3 is a back view of the shoe sole of FIG. 1.

FIG. 4 is a left view of the shoe sole of FIG. 1.

FIG. 5 is a right view of the shoe sole of FIG. 1.

FIG. 6 is a top view of the shoe sole of FIG. 1; and,

FIG. 7 is a bottom view of the shoe sole of FIG. 1.

The broken lines are included for the purpose of illustrating environmental structure and form no part of the claimed design.
